UNITED STATES PATENT OFFICE

JOHN W. ERHARD AND ANTOINETTE ERHARD, OF NEW YORK, N. Y.

BATHTUB SEAT

Application filed May 12, 1930. Serial No. 451,550.

This invention relates generally to new and novel improvements in bath tub seats.

The invention has for an object the provision of a bath tub seat adapted to be readily disposed within a bath tub so as to add to the comfort of a person taking a bath.

The invention has for a further object the provision of a bath tub seat of simple durable construction which is desirable and convenient in use, and which can be manufactured and sold at a reasonable cost.

The invention consists in a seat structure provided with means for supporting same in a bath tub at one end thereof, or the other end, or any intermediate portion. This seat structure is preferably supported at a height convenient for a bather to sit while washing certain portions of his body, such as his feet. The bather may use the seat as a head rest while lying in the tub. The seat structure is provided with hooks engageable with the top edges of the bath tub and arranged for pivoting or being locked in fixed positions. The seat structure may also have a supporting leg engageable against the bottom of the tub.

For further comprehension of the invention, and of the objects and advantages thereof, reference will be had to the following description and accompanying drawings, and to the appended claims in which the various novel features of the invention are more particularly set forth.

Referring to the accompanying drawings, forming a material part of this disclosure:

Fig. 1 is a perspective view of a bath tub provided with the device.

Fig. 2 is a perspective view of the bath tub seat itself.

Fig. 3 is a perspective view of a modified form thereof.

Fig. 4 is a perspective view of a still further modified form.

Fig. 5 is a front view of the device shown in Fig. 2, but illustrating a modification thereof.

Fig. 6 is a fragmentary front view of the device shown in Fig. 3.

Fig. 7 is an enlarged detail fragmentary sectional view of a portion of Fig. 6.

Fig. 8 is an enlarged fragmentary perspective view of the hook used in the devices.

Fig. 9 is a fragmentary vertical sectional view, taken on the line 9—9 of Fig. 8.

Fig. 10 is a fragmentary vertical sectional view, taken on the line 10—10 of Fig. 8.

The reference numeral 10 indicates generally a bath tub of any design or shape, having an upper rim 11 preferably of curved cross-section. A seat structure 12 is supported from this upper rim. This seat structure consists of a seat 13, a seat back 14 connected therewith, and side arms 15 secured to the seat and seat back. Hooks 16 hereafter described in detail are attached to the upper part of the seat back, and engage over the upper edge 11 of the bath tub, holding the seat structure in place. The seat structure may be of rubber or leather, and the hooks of nickel plated metal. It is thought that the most desirable position of the seat would be about 9 inches from the floor of the bath tub.

The modification illustrated in Fig. 3, discloses a seat 17 of rectangular form, provided with a plurality of hooks 16 connected on opposite sides by bars 18, and capable of supporting the seat upon the upper edge of the tub, anywhere along its length. Fig. 4 illustrates a seat 17' of circular shape provided with the hooks 16.

The modification illustrated in Fig. 5 discloses the seat structure 12 provided with a flange 19 attached to the seat 13, a rod 20 projecting from the flange, a coupling 23 threadedly engaged to the rod, a second rod 21 threadedly engaged in the coupling and a flange 22 on the bottom of rod 21, the threads on rod 20 being right-handed, and on 21 left-handed.

Figs. 6 and 7 show in detail that the hooks 16 are pivotally arranged as at 16^a by pintles 24 rigidly and stationarily fixed on the bottom of the hook and rotatively engaging in material adjacent the hook. Each pintle 24 has an aperture 25 engageable by the top end of a rod 35 for holding the hook 10

in a vertical position. Each rod 35 is pivotally connected at its bottom to one end of a seat lever 36 pivoted intermediate of its ends as at 37.

- 5 The upper rim 11 of different bath tubs may be of different curvatures. Figs. 8, 9 and 10 illustrate the hook 16 in detail as capable of neatly engaging any upper rim 11. These hooks consist of a plurality of 10 adjacent pieces 26, and the adjacent edges include a tongue 27 from one piece engaged between a pair of tongues 28 from the other piece. The tongue is formed with an aperture 29 and a plurality of keyways 30 connecting therewith. The tongues 28 are formed with apertures 31 and one keyway 32 therein, connected with the aperture. A shaft 33 with a key 34 engages these apertures, the key 34 engaging the keyways 32 15 and one of the keyways 30. The shafts and keys may be removed and reset so as to change the angular relation of the pieces.

The permanent pivotal joints 16^a of the hooks are frictionally tight for maintaining 20 vertical positions of the hooks 16 which are thus locked when a person sits on the seat and upon the seat levers 36 which causes the locking rods 35 to engage in the apertures 25. When the seat is not in use the 25 hooks 16 may be manually turned downwards about hinge points 16^a and thus the device conveniently stored away.

While we have above described the preferred form, construction and arrangements 30 of the several elements employed, it will be understood that the device is, nevertheless, susceptible of considerable modification therein, and we therefore reserve the privilege of resorting to all such changes as 35 may be fairly embodied within the spirit and scope of the invention as claimed.

Having thus described our invention, what we claim as new, and desire to secure by United States Letters Patent is:—

- 40 1. A bath tub seat, comprising a seat member, arms connected therewith, a plurality of adjacent hook pieces connected to the ends of the arms, these pieces being provided at their adjacent edges with a tongue 45 from one piece engaging between a pair of tongues from the other piece, the first mentioned tongue being provided with an aperture and a plurality of keyways connected therewith, the pair of tongues being provided with an aperture and one keyway connected therewith, and a shaft with a key engaged in the said apertures, and certain of the keyways for holding the pieces at angular relations to each other.
- 50 2. A bath tub seat, comprising a seat member, arms connected therewith, a plurality of adjacent hook pieces connected to the ends of the arms, these pieces being provided at their adjacent edges with a tongue 55 from one piece engaging between a pair of

tongues from the other piece, and a means for holding the said tongues at angular relations to each other to form hooks of a desired curvature.

3. A bath tub seat, comprising a seat arranged to be supported on the top rim of a bath tub by hooks pivotally mounted and arranged to frictionally maintain vertical positions, a means for latching the hooks into vertical positions when a person sits 75 on the seat.

4. A bath tub seat, comprising a seat arranged to be supported on the top rim of a bath tub by hooks pivotally mounted and arranged to frictionally maintain vertical 80 positions, a means for latching the hooks into vertical positions when a person sits on the seat, comprising seat levers pivotally mounted, and rods connected with the seat levers and arranged for engaging in apertures in the hinge members of the hooks. 85

5. A bath tub seat, comprising a seat arranged to be supported on the top rim of a bath tub by hooks pivotally mounted and arranged to frictionally maintain vertical 90 positions, a means for latching the hooks into vertical positions when a person sits on the seat, comprising seat levers pivotally mounted, and rods connected with the seat levers and arranged for engaging in apertures in the hinge members of the hooks, 95 said hooks being arranged to assume various fixed adjusted positions.

6. A bath tub seat, comprising a seat arranged to be supported on the top rim of a bath tub by hooks pivotally mounted and arranged to frictionally maintain vertical 100 positions, a means for latching the hooks into vertical positions when a person sits on the seat, comprising seat levers pivotally mounted, and rods connected with the seat levers and arranged for engaging in apertures in the hinge members of the hooks, 105 said hooks being arranged to assume various fixed adjusted positions, by reason of being formed of a plurality of separate sections joined and held together.

In testimony whereof we have affixed our signatures.

JOHN W. ERHARD.
ANTOINETTE ERHARD.
